UNITED STATES PATENT OFFICE.

WILLIAM H. DANA, OF DAYTON, OHIO, ASSIGNOR TO LEOPOLD RAUH, OF DAYTON, OHIO.

VOTING-MACHINE.

No. 845,860.

Specification of Letters Patent.

Patented March 5, 1907.

Application filed May 6, 1903. Serial No. 155,898.

To all whom it may concern:

Be it known that I, WILLIAM H. DANA, a citizen of the United States, residing at Dayton, in the county of Montgomery and State 5 of Ohio, have invented certain new and useful Improvements in Voting-Machines, of which the following is a full, clear, and exact description, reference being had to the accompanying drawings, forming part of this 10 specification.

My invention relates to machines for registering mechanically the selection by voters of various candidates to be elected at any election in which all of the candidates of the 15 various parties are presented to the voter under the Australian-ballot system, the voter registering his choice by the operation of keys or levers, one for each candidate.

In the construction of voting-machines 20 adapted for use generally under the election laws of the various States and for all classes of elections where many tickets may be in the field, each containing a large number of names of candidates, many requirements are 25 necessary, all of which I have endeavored to present in my novel construction of machine, the general principles and the various details of which will be hereinafter particularly pointed out and claimed. Some of these re-

30 quirements are that the balloting must be in secret, and when a voter has made his selection and passed from the booth his vote must be recorded and all evidence of his choice must be destroyed. The voter must be allowed 35 to vote for straight tickets, split or scratched tickets, for candidates of his own selection whose names do not appear on any of the regular tickets. He must be allowed to vote on various questions submitted, and

40 certain classes of voters, while they can enter the booth and operate the machine in secret, must be excluded from voting for certain candidates for certain offices and from voting on certain questions. Provision must also

45 be made to prevent voting for more than the proper number of tickets to prevent repeating and at the same time to allow the voter to select any names he may wish from a group of tickets when a plurality are to be selected 50 for any office. These requirements are, I believe, generally known in the art as provisions for voting straight tickets and split tickets and for regular, question, exclusion, and multiple voting.

Election-tickets often present forty or fifty 55 names, and seven or more regular tickets are often in the field, so that economy of space is demanded that all parts of the machine may be within easy access of the voter.

The mechanical operation must be exceedingly accurate and very little, if any, dependence should be placed on multiplicity of springs. Complication of parts must be avoided and the various mechanisms should be easily assembled and be readily accessible for setting up the multiple and exclusion devices and other parts before each election to conform to the arrangement of names on the ballots. Counting or registering mechanism, inasmuch as there must be one counting 60 device for each name on the tickets, must be so arranged as to be readily and quickly reset and the machine must be capable of being prepared for any election by any ordinary 65 mechanic. The keyboard or the front of the 70 machine should be open to the inspection of the judges when not in use and at such times should be always locked, and it should be well-nigh impossible for any ignorant or dishonest voter to tamper with the machine or 75 to block its operation during the progress of 80 any election.

In constructing my machine in presenting the lists of candidates to the voters I have followed the more familiar arrangement of 85 the Australian ballot in arranging the lists of candidates under each ticket in vertical rows, with the various offices for which the selection is to be made in horizontal rows, and I have divided the machine into three sections, 90 one for the regular tickets, second for the question-voting, and third for the irregular voting. Separate mechanisms are employed 95 for these three sections coöperating in certain respects.

While I have provided space in the general plan of the machine illustrated for the irregular-voting mechanism, I have omitted from the present application any illustration or description of this mechanism, deeming it 100 best to make this feature of my machine the subject-matter of a separate application to be filed. I have also at the request of the Commissioner divided out of the present application for the purpose of a divisional application 105 the exclusion or limited franchise apparatus, and for the purpose of filing separate divisional applications I have also erased

from the present application all such constructions as relate particularly to the multiple-voting devices, and while for the proper understanding of the apparatus I have retained the description of the voting-booth construction I have also erased for the purpose of division all claims relating particularly to the booth construction.

In the drawings, Figure 1 is a perspective view of the booth open, showing the face of the keyboard. Fig. 2 is a perspective view of the booth from the rear with the curtain closed. Fig. 3 is a front elevation of the machine with the lower portion broken away. Fig. 4 is a vertical section on the lines 4-4 of Fig. 3. Figs. 5 and 6 are detail views, full size, of the voting-keys, showing one key in each view in the position after being voted. Fig. 7 is a rear elevation of the machine with the closing casing and two register-frames removed. Fig. 8 is a horizontal cross-section taken on the lines 8-8 of Fig. 7. Fig. 9 is a full-sized sectional side elevation of the registering mechanism, taken on the lines 9-9 of Fig. 7. Figs. 10, 11, 12, 13, and 14 are detail views of portions of the counting mechanism. Fig. 15 is a rear elevation of a portion of the machine, showing the lever for voting straight tickets. Fig. 16 is a perspective view of the abutment-plates attached to the end sliding or interfering blocks. Fig. 17 is a perspective view of the parts comprising the voting-lever mechanism from the rear. Fig. 18 is a perspective view of a portion of the key-plate from the rear. Fig. 19 is a perspective view of one of the supporting-plates for the registering mechanism.

The voting-machine is set up in a rectangular booth made of a light framework, the machine itself forming one side of the booth and the other three sides being concealed by curtains A, hung from the top of the frame. The curtain on one side, B, is loose and capable of being thrown to one side, as shown in Fig. 1, the folds of the curtain falling within the forks of a bifurcated lever C, mounted on the outer end of a shaft D, journaled in the base of the machine. When this lever is down, as shown in Fig. 2, the curtain B drops behind the overlapping portion of the curtain A, which extends a slight distance beyond the corner on this side, so as to completely inclose the booth. When the lever C is raised, as shown in Fig. 1, the voting-machine is in full view of the judges of the election, and the curtain is draped in folds at one side.

As will be hereinafter described, the shaft D controls the registering mechanism, which in turn locks the voting-levers when the lever C is raised, so that when the booth is open the machine is locked. When the lever C is down, the voting-machine is unlocked.

The machine itself is mounted in a rectangular frame comprised of sides E E and top and bottom base F and G, the lower end of

the sides E E being properly supported by standards H H. Running vertically and securely fastened to the top and bottom of the frame are the plates I I, (shown in Fig. 3,) spaced apart and forming the wall of the machine. Immediately back of this wall are secured between the sides E E the bars L L, (shown in Figs. 3 and 4,) which bars are provided with channels or longitudinal side grooves for the purpose to be described. These vertical plates I and horizontal channel-bars L form the framework of the machine in which and upon which are mounted the operating parts.

Secured at top and bottom to the frame between the spaces between the plates I I are the vertical key-bars M, which carry the key-levers. A portion of one of these bars is shown in Fig. 18 from the rear, and the side edges are formed with a longitudinal channel a a, forming a space to hold the various tickets.

I have illustrated in the machine spaces for two tickets which I have denominated "Republican" and "Democratic;" but of course it will be understood that the framework is wide enough to hold as many tickets as there may be at any election. The names of the candidates for each ticket are printed on separate slips of the proper width to slide in the channel in the key-plates, and the names of the offices are also printed on a slip and inserted the same way as the tickets, either from top or bottom to the left of the tickets. It is thus a very simple matter to arrange the face of the machine for any election. The retaining-plates b b at the top and bottom of the machine are removed and the tickets slipped into place and the retaining-plates again secured. The machine is arranged for any necessary length of ticket; but if there are not many names on the tickets the lower portion of the machine is not used. The blank space N on the left of the voting-machine, as shown in Fig. 3, is intended for the irregular voting-devices, which, as I have already stated, I have omitted from the present application. The rear of the machine is inclosed by a glass window O, (shown in Fig. 4,) through which the judges can examine and take off the vote registered on the counters without any access to the counting mechanism, and this window is inclosed by the doors P P, locked with keys in possession of the judges, which doors are hinged to the side frames, so that only the judges can examine the count of the machine.

The voting-levers are mounted for each row of tickets in the key-plates M in the diagonal slots c c. (Shown in detail in Fig. 18.) These levers are supplied one for each name and for the answer to each question, and consists of a shank portion d with an enlarged button-like head e, made smooth and round in order to prevent anything being

wedged between the key-levers, and the buttons are of sufficient diameter to cover the slots *c c*, through which the shanks pass, in whatever position the lever may be in order that there may be no opportunity for any one to insert anything through the slots *c* to block the machine. The back of the plates *M* are provided with a slightly-diagonal groove *f*, one for each key, in which rides the bar *g*, attached to the shank of the key-lever. On the rear face of this guide-bar *f* is secured a horizontally-disposed channel-bar *h*, which engages the central pin *i* on the longer toggle-lever *j* of the pair of toggle-levers *j k*. The outer end of the toggle-lever *j* is mounted on a stud *l* on the far side of the block *R*, while the smaller member *k* is pivoted on the stud *m* on a similar abutting block *R*, with its inner end coupled on the pin *i*. These blocks *R*, one for each voting-lever, are mounted to slide horizontally in the channel-bars *L*. In order to conveniently mount these sliding blocks *R* in the respective channels in the channel-bars *L*, the channel is cut away at one end, as shown at *m* in the upper corner of Fig. 8. Each of these blocks *R* is cut away at one end, as shown at *n* in Fig. 17, to allow for the passage of the pin *i* on the toggle-lever *j*, and each row of sliding blocks is held normally with the sliding blocks abutting by securing the sliding block at one end of the row to the vertical plate *I* and connecting the sliding block at the other end of the row to the fixed vertical plate *I* by a coiled spring *p*, the coiled spring to allow the blocks to be separated, but returning them to their normal position with their ends abutting when released. The free sliding block at the end of each row is provided with an abutment-plate *S*, mounted on studs *r r*, and these abutment-plates are provided with slots *s*, as shown in Fig. 16. *T*, Fig. 7, is a vertical bar secured to the top and bottom frame of the machine and running across these abutment plates *S* and carrying pins *t t*, one for each row of sliding blocks, the ends of the pins passing through the slots *s* in the abutment-plates. These slots *s* are of sufficient length to allow for the lateral movement of the row of sliding blocks sufficient to permit one set of toggle-levers *j k* to be spread apart by the pulling down of the lever-key acting on the pin *i*, engaged by the channel-guide bar *h* on the key-lever; but the slot is not sufficiently long to permit any other set of toggles in that particular row to be operated. This construction forms what I have called the "unit-stop voting device." The toggle-lever construction which I have illustrated in connection with the sliding blocks forms a very effective method of spreading apart the sliding blocks and preventing the operation of more than one voting-key in any horizontal row. It will be evident that the coiled springs which I have described as

acting on the free end of the sliding blocks in each row will keep the voting-levers in their normal unvoted position, and when one lever is pulled down, unless fully voted, the spring will return the voting-lever; but when fully voted the central pin *i*, upon which the two toggles are coupled, will be slightly below the pivot-studs *n l*, and the voting-levers will therefore be held down when fully voted.

It is of course essential for a voting-machine that there should be a counter for each name, and it is also essential that the numbers required on the counters shall be in convenient position for taking off the number of votes registered for each candidate, and then after each election the counters may be conveniently reset to zero. As already stated, my tickets are preferably arranged in vertical rows, and for each ticket I provide what I call a "register-frame," which frame shall contain all of the counters for the candidates on the particular ticket. I have illustrated only two tickets and the question-voting mechanism in the drawings, and I therefore show three counter-frames. All of the counter-frames are alike, and a description of one will apply to all. The general principle of operation I have adopted is to rotate or move the actuating-pawls for the counting-wheels into the pathway of the voting-lever mechanism in order to affect the registration of all voting-levers that may have been operated and this movement is accomplished by the voter as he leaves the booth raising the bifurcated lever, which folds back the curtain inclosing the entrance side of the booth. This lever *C*, I have already described as being secured to the shaft *D*, which is journaled in suitable bearings on the bottom frame of the case.

The register-frame for each ticket is illustrated in detail in Fig. 9, and the various parts of the counting mechanism are shown in Figs. 10 to 14. The register-frame is made up of a top disk *B'*, carrying a hub-collar *f'* and a bottom disk *C'*, also having a hub-collar *g'*. *D* is a vertical shaft connecting these two disks, secured by a pin *h'* at the bottom and screw-threaded at *i'* at the top, upon which is mounted the nut *k'*, the nut being journaled in the collar *l'*, secured by a set-screw *m'* to a stud *E'*, secured to the top of the frame. By loosening the collar *l'* and sliding it up the register-frame, with its central shaft, can be readily disconnected from the machine, the collar *g'* at the bottom being slotted, as shown at *n'* in Fig. 4, to receive the tongue on a short shaft *F'*, mounted in a yoke *G'*, secured to the standard holding the shaft *D*. This shaft *F'* carries the bevelled gear *H'*, which meshes with the gear *L'*, secured on shaft *D*. As the shaft *D* will be rocked a quarter of a revolution by the raising and lowering of the lever *C*, holding the

BEST AVAILABLE COPIE

4

845,860

curtain, by means of these beveled gear, the register-frame for each ticket will be rotated about a quarter of a revolution. The individual counting mechanisms—one for each name on the ticket—are strung on the vertical shaft D. These counting mechanisms are mounted on and separated by the disk plates M'. (Shown in perspective in Fig. 27.) These disk plates carry studs o', which fit into corresponding recesses in the plate immediately above, and in addition to the clamping together accomplished by screwing up the nut k' on the shaft D' rods p' are also strung through the plates at the periphery and clamped by nuts to obtain a rigid frame. The counters are ratchet-wheels r', Figs. 12 and 13—three for each name—carrying numerals on the periphery and strung on the shaft N', running from the top to the bottom of the register-frame parallel to the central shaft D', each set of three counters being separated by the disk plates M'. These counters represent the units, tens, and hundredths wheels, and the units and tens wheels have one tooth deeper than the normal teeth of the wheel, the depth of these teeth being shown at s' t' in Figs. 12 to 13. The counters are actuated by the three-stepped pawl u', pivoted on one arm of a pawl-carrier v', having a central hub w', strung on the shaft D'. This pawl-carrier has a segmental contact-plate y', which is actuated by the voting-lever mechanism, as will be hereinafter described. a'' is a flat spring secured to the pawl-carrier and bearing against a lip b' at the rear end of the pawl u' to keep this pawl in contact with the counting-wheels r'. It will be evident that as the pawl-carrier is actuated the pawl u' will advance the units-wheel, which is the lowest of the three, until the deep tooth t' is reached, when the middle step on the pawl u' will be brought into play to advance the tens-wheel one tooth, and when the deeper teeth in both the units and tens wheel are together the hundredths wheel will be advanced one tooth, so that each counter consisting of three wheels will register to nine hundred and ninety-nine. As the actuating position of the pawl u' is fixed, the movement of the pawl-carrier will bend the spring a'', so that when the pawl-carrier is released it will return to its normal position under the pressure of this spring. c'' is a spring-plate with three teeth secured to the lip a' on one of the studs o', which spring bears on the faces of the ratchet-teeth of the counters and prevents any back movement of the ratchet-wheels. For the purpose of resetting the counters to zero I form a longitudinal groove d'' in the shaft N', running from top to bottom, so as to form a shoulder on this shaft. Then each ratchet-wheel is formed with an annular recess e'', leaving a hub portion f'', which is slotted or opened at g''. In this annular recess in each ratchet-

wheel I mount the spring-band h'' with one end l'' turned in through the slot g'' in the hub of the ratchet-wheel, so that it will engage in the longitudinal groove in the shaft N'. The ratchet-wheels can turn in the proper direction, and the spring-shafts h'' slide out of the groove; but when the shaft N' is turned by the thumb-nut P' in the opposite direction the inwardly-projecting ends of the spring-bands h'' will catch against the shoulder formed by the longitudinal groove in the shaft N', so that the several ratchet-wheels will be picked up by the shaft and rotate with it. The slots g'' are formed in the same position for each ratchet-wheel at the same number, and all of the ratchet-wheels of all of the counters on the shaft will therefore with one rotation of the shaft by the thumb-nut P' be returned to zero.

The register-frame, carrying the counting mechanisms, as above described, is located in such a position with reference to the voting-lever mechanism that the pin m'', Fig. 17, on the toggle j will project within the register-frame. When these pins m'' are raised—that is, when the voting-levers are in their normal position—the rotation of the register-frame by the beveled gears will not affect the counting mechanism; but when the register-frame is in the unlocked position, with the booth closed and lever C horizontal, the pulling down of any of the voting-levers will bring the corresponding pins m'' on the toggle into the lower portion of the counting-frame, and the rotation of the register-frame will cause all of the toggle-pins that are down to actuate the segmental contact-plates y' of the counter pawl-carrying mechanism. The disk plates M' each are formed with a peripheral cam-shaped flange n'', located in the pathway of the toggle-pins m'' when the register-frame is rotated. These pins therefore ride back on the edge of this cam, rotating the pawl sufficient to advance the counting-wheel one tooth, and then they are raised out of contact with the segment-plates y' and rest on top of the flange. When the toggle-pins m'' rest on top of the flanges n'', it is very evident that none of the voting-levers can be operated, and the machine will be securely locked. This is the position the rotating register-frame takes when the lever C is raised. In order to prevent any person seeking to wreck the machine—pushing the toggle-pins m'' down behind the segment-plates y''—these segment-plates are made long enough to overlap or pass in behind the flanges on the disk plates M'', as shown in Fig. 9.

For straight-ticket voting, I provide as shown in Fig. 15. L'' is a vertical bar guided by the slots f''', engaging screws g''', secured to the top and bottom of the frame, and this bar carries a series of arms h''', one for each pin m'' on the toggle-lever for each

candidate, while this bar is operated by an arm l'' , actuated by the pin m'' on the guide-bar n'' , which slides vertically in a suitable vertical groove in the rear of the 5 key-plate M, the bar being actuated by the voting-lever button p'' , opposite the name or ticket-emblem of each straight ticket. By pulling down these straight-ticket buttons the straight-ticket bar L'' thus operates 10 all of the voting-levers in the selected vertical row. To vote for a straight ticket, with the exception of a few selected names from some other ticket, the straight-ticket key is voted, and for any selected horizontal row 15 the voter returns the individual key-lever in the straight-ticket vertical row and votes the individual lever opposite the name or names selected in the other tickets. A spring r'' , Fig. 9, secured to the bottom plate, bears 20 against the lower end of the straight-ticket bar to return it to its normal position.

The operation of the machine has been rather fully described in connection with the description of the mechanism; but it may be 25 well to briefly sum up the various functions. The voting-booth normally stands open, as shown in Fig. 1, and in this position the register-frames are all rotated by the shaft D, meshing through the beveled gears with the 30 vertical shafts upon which the register-frames are mounted, so that the flanges n'' on the division register-plates M' are underneath the toggle-pins m'' on the toggle-levers of all of the key-levers both for candidates and questions. When the voter enters 35 the booth, he brings the operating-lever C into horizontal position and the curtain B drops of its own weight to conceal the voter. This movement of the lever C rotates all of 40 the register-frames and carries the flanges m'' from under the toggle-pins, thus unlocking the machine. If the voter wishes to vote a straight ticket, he pulls down the straight-ticket button, which through the straight-ticket bar pulls down all of the voting-levers 45 in the vertical ticket-row. As shown in Figs. 5 and 6, the word "Voted" is printed on the key-plates, and when the ticket-levers are drawn down this word "Voted" appears, so 50 that the voter knows that he has expressed his choice. As already described, however, the operation of the voting-levers only sets the toggle-pins in a position to contact with the pawl-carrier of the several counting mechanisms, so that as long as the voter remains 55 in the booth, he can change his vote. In order to leave the booth, the voter raises the lever C, which folds back the movable curtain, and this movement rotates all the register-frames and such voting-levers as have 60 been operated register on their respective counters. For single-candidate offices, which will appear in a single horizontal row, the abutment-plates for the sliding blocks of

each row have been previously locked by the 65 pins on the units-voting bar, so that there is room for the actuation of but a single pair of toggle-levers in such row. After the election is over a padlock is passed through the staple l'' and the opening m'' in the outer end of 70 the lever C, and the machine is thus locked for the time required by law to preserve a record for contests or otherwise, and the door P in the rear of the machine is then opened, which exposes through the glass window O 75 the numbers on the counters in the register-frames. In order that there may be no confusion in taking off the vote, a plate M'', Fig. 7, is provided on the register-frame, carrying a letter and number to indicate the candidate for whom the count on the regular 80 counting device has been made, the numbers corresponding to the number of the horizontal rows on the front of the machine.

As has already been noted in connection 85 with the description, the various parts are constructed so as to be readily and easily assembled in building the machine. The vertical bars forming the wall of the machine are merely screwed to the top and bottom 90 frame, the channel bars carrying the sliding plates are screwed to the side walls of the frame, the sliding-plates are inserted into the channels in these plates, the key-plates carrying the key-levers, with the diagonal 95 guide-bar and horizontal channel-bar, are screwed to place with the central toggle-pins engaging in these channel-bars, the units stop-bar, with its stop-pins, is screwed to the top and bottom of the frame, while the several 100 tickets when inserted in front cover up all the screws except those of the top and bottom bars, by which bars they are clamped in place.

The several register-frames are readily set 105 up, the counters being strung on the counter-shaft and the pawl-carriers with the pawls on the central shaft, with the division-plates between each three counting-wheels. The actuating-shaft D, with its beveled gear L, is 110 mounted in place, and the register-frames are then easily secured in vertical position. The straight-ticket bar is mounted in vertical position. By rotating the shaft M', upon 115 which the counters are strung, by the thumb-nut P', the counters in each register-frame are at once reset to zero, and the machine is ready for operation.

The mechanism for all the operating parts can be gotten at separately for cleaning or 120 otherwise, and the several register-frames can be easily removed when it is desired to store them between elections. The registering or counting portion of the voting-machine is of course one of the most important 125 parts of the machine and should be kept in perfect order and condition, and it would be very proper after each election to remove

from the machine the register-frames and counting mechanism and to wrap them up in flannel or otherwise and lay them away in boxes specially provided, and they can then 5 be stored in any suitable safe for preservation. Other parts of the operating mechanism can also be readily removed for storage, leaving only the framework and less important parts to be stored with the booth in such 10 available places as there may be.

Having thus described my invention, what I claim, and desire to secure by Letters Patent, is—

1. In a voting-machine, a series of key- 15 plates one for each ticket, elongated slots therein, with key-levers mounted in said slots, said key-levers having enlarged button-like heads to cover the slots in the plate in any position of the key-levers, substantially 20 as described.

2. In a voting-machine, a series of key- 25 plates, one for each ticket, with key-levers mounted in slots therein, grooves in the rear face of the key-plates, with bars on the key- levers riding in said grooves to guide the key- 30 levers, an interlocking device to prevent simultaneous operation of more than the pre- determined number of key-levers, and means for connecting the key-levers to said inter- locking device to permit shifting thereof without disconnection, substantially as de- scribed.

3. In a voting-machine, a plurality of voting-keys, with individual counting devices 35 for each key, and a rotatable register-frame upon which the individual counters are mounted, with means for rotating the register-frame to cause all operated voting-keys to actuate their respective counters, substan- 40 tially as described.

4. In a voting-machine, a plurality of voting-keys and a rotatable cylindrical frame, with partitions for dividing same into unit- 45 frames corresponding to the number of vot- ing-keys for each ticket, a set of counters, with means for operating same, mounted in each unit-frame, and means for rotating the entire register-frame to cause all operated keys to actuate their respective counters, 50 substantially as described.

5. In a voting-machine, a plurality of voting-keys and a rotatable register-frame, a shaft longitudinally supported in said frame, with sets of counting-disks strung on said 55 shaft, the sets separated from each other and forming individual counters for their respective voting-keys, and means for rotating the register-frame to cause all operated keys to actuate their respective counters, substan- 60 tially as described.

6. In a voting-machine, a plurality of voting-keys and a rotatable cylindrical frame, with partitions for dividing same into unit-frames, corresponding to the number of vot- 65

ing-keys for each ticket, a shaft running longitudinally through said register-frame, with sets of counters strung on said shaft, one set for each unit-frame, and means for rotating the register-frame to cause all operated keys to actuate their respective counters, substan- 70 tially as described.

7. In a voting-machine, a plurality of voting-keys arranged in a row and a rotatable register-frame, a shaft mounted in said frame with sets of counting-disks strung on said 75 shaft so as to turn loosely thereon in one direction, the said sets of counters separated from each other and forming individual counters for their respective voting-levers and means for rotating the register-frame to cause all operated keys to actuate their respective counters, and an individual clutch interposed between each counting-disk and the supporting-shaft to couple same to the shaft when turned in an opposite direction, 80 whereby all the counters for the row of voting-levers may be simultaneously reset to zero, substantially as described.

8. In a voting-machine, a plurality of voting-keys arranged in a row, a register-frame 90 with central shaft by which said frame is rotated, a second shaft in said frame parallel to the central shaft, with sets of counting-disks strung on said second shaft and separated from each other to form individual counters 95 for their respective voting-levers, actuating devices for the counters strung on the central shaft, one for each individual set of counters, and means for rotating said register-frame to cause all operated voting-levers to 100 operate their respective counter-actuating devices, substantially as described.

9. In a voting-machine, a plurality of voting-keys arranged in a row, a register-frame with central shaft by which said frame is rotated, a second shaft in said frame parallel to the central shaft with sets of counting-disks strung on said second shaft and separated from each other to form individual counters 105 for their respective voting-levers, pawl-carriers one for each individual set of counters strung on the central shaft with pawls thereon, one for each carrier, to engage said counters, with intermediate mechanism inter- 110 posed between the pawl-carriers and voting- 115 levers normally inoperative but arranged to be set by the operation of the key-levers, and means for rotating the register-frame to cause said intermediate mechanism set by the operation of the key-levers to actuate 120 their respective pawl-carriers to register the key movements, substantially as described.

10. In a voting-machine, a cylindrical frame with counting mechanisms mounted thereon, and means for rotating said frame to 125 actuate the counters, said cylindrical frame having hub portions at each end and means for removably securing said hubs to said ro-

tatable mechanism, whereby the frame and counting mechanism may be readily removed from the machine, substantially as described.

11. In a voting-machine, a cylindrical frame, with counting mechanisms mounted thereon, shaft and gearing for rotating said frame, hub portions at each end of said frame, with tongue-and-groove connection at one end and collar and set-screw connection at the other with said rotating shaft, whereby the rotatable frame may be readily connected to and disconnected from said gear-driven shaft, substantially as described.

12. In a voting-machine, a cylindrical register-frame for holding the counting mechanisms, said frame consisting of end disks and central shaft with intermediate disk plates strung on said shaft, each intermediate disk provided with lugs to fit into the adjoining disk and subdivide the main frame into unit-frames, substantially as described.

13. In a voting-machine, a plurality of key-levers, with individual counting devices for each lever, and a rotatable register-frame upon which the individual counters are mounted, an operating-lever outside the voting-machine, and connecting mechanism intermediate said lever and register-frame, whereby the movement of the booth-lever will rotate said register-frame to cause all operated key-levers to actuate their respective counters, substantially as described.

14. In a voting-machine, a plurality of voting-levers with individual counting devices for each key-lever, and a rotatable register-frame upon which the individual counters are mounted, said register-frame carrying cam-plates one for each individual counting device, with means for rotating said register-frame to cause all operated key-levers to actuate their respective counters and to contact with said cam-plates to be returned to their normal position, substantially as described.

15. In a voting-machine, a plurality of key-levers, with individual counting devices for each lever, and a rotatable register-frame upon which the individual counters are mounted, a booth within which the voting-machine is mounted, a lever closing the entrance to said booth, and connecting mechanism intermediate said lever and register-frame, whereby the movement of the booth-lever will rotate said register-frame to cause all operated key-levers to actuate their respective counters, substantially as described.

16. In a voting-machine, a plurality of voting-levers, with individual counting devices for each key-lever, and a rotatable register-frame upon which the individual counters are mounted, said register-frame carrying cam-plates one for each individual counting device, a booth within which the voting-ma-

chine is mounted, a lever closing the entrance to said booth, and connecting mechanism intermediate said lever and register-frame, whereby the movement of the booth-lever will rotate said register-frame to cause all operated key-levers to actuate their respective counters, substantially as described.

17. In a voting-machine, a plurality of key-levers, with individual counting devices for each key-lever, and a rotatable register-frame upon which the individual counters are mounted, said register-frame carrying cam-plates one for each key-lever, an operating-lever outside the voting-machine and connecting mechanism intermediate said lever and register-frame, said cam-plates normally in the pathway of said key-levers to lock same from operation when said operating-lever is in one position, but removed therefrom by the rotation of the register-frame when the lever is operated to permit operation of the key-levers, substantially as described.

18. In a voting-machine, a plurality of key-levers, with individual counting devices for each key-lever, and a rotatable register-frame, upon which the individual counters are mounted, said register-frame carrying cam-plates, one for each key-lever, a booth within which the voting-machine is mounted, a lever closing the entrance to said booth and connecting mechanism intermediate said lever and register-frame, said cam-plates normally in the pathway of said key-levers, to lock same from operation when the operating-lever is raised to open the booth and when lowered to close the booth said cam-plates being removed to permit operation of the key-levers, substantially as described.

19. In a voting-machine, a plurality of key-levers, with individual counting devices for each key, a rotatable register-frame upon which the individual counters are mounted, said frame carrying plates to block the movement of the keys, and means for rotating said frame to release the keys for operation, substantially as described.

20. In a voting-machine, a plurality of key-levers, with individual counting devices for each key, a rotatable register-frame upon which the individual counters are mounted, said frame carrying cam-plates to return to their normal position all operated keys and to block the movement of all the keys, with means for rotating said frame in both directions to release the keys for operation when rotated in one direction and to return all operated keys and block the movement of all keys when rotated in the opposite direction, substantially as described.

21. In a voting-machine, a plurality of voting-levers, with individual counting devices for each key-lever, and a rotatable register-frame upon which the individual counters are mounted, said register-frame carrying

cam-plates to return to their normal position
all operated keys and to block the movement
of all the keys, and an operating-lever outside
the voting-machine, and connecting mechan-
ism for rotating said frame in both directions
5 to release the keys for operation when rotated
in one direction and to return all operated

keys and block the movement of all keys
when rotated in the opposite direction, sub-
stantially as described.

WILLIAM H. DANA.
